ATION OF MAINE.

WARP STOP-MOTION FOR LOOMS.

1,013,966.

Specification of Letters Patent.

Patented Jan. 9, 1912.

Application filed March 31, 1911. Serial No. 618,217.

To all whom it may concern:

Be it known that we, WALLACE I. STIMPSON and ALONZO E. RHOADES, both citizens of the United States, and residents of Hopedale, county of Worcester, State of Massachusetts, have invented an Improvement in Warp Stop-Motions for Looms, of which the following description, in connection with the accompanying drawing, is a specification, like characters on the drawing representing like parts.

This invention has for its object the production of a warp stop-motion for looms so constructed and arranged that when the loom is stopped by a warp fault the weaver can readily note in which one of a plurality of banks of detectors is located the released or active detector, so that the faulty warp-thread can be found promptly.

20 In the ordinary form of double-bank stop-motion apparatus wherein the detectors are suspended from the warp-threads and are almost wholly below the warp the construction is such that it is very hard for the 25 weaver to ascertain readily where the released detector is located, for if it is in the rear bank it is covered by parts of the mechanism in front, and if in the front bank the arrangement of the feeler device obstructs 30 the view.

In our present invention we have so arranged the feeling instrumentality that a clear view of the front bank of detectors can be had at all times, and by certain 35 changes and novel features of construction we have provided for a substantially unobstructed view of the lower ends of the detectors of the rear bank, so that a released detector in such rear bank can be seen with 40 comparative ease.

We have also devised certain novel structural features whereby the warp stop-motion as a whole is improved.

The novel features of our invention will 45 be fully described in the subjoined specification and particularly pointed out in the following claims.

Figure 1 is a left-hand side elevation and

part section of a portion of a loom, provided with a warp stop-motion embodying our 50 present invention; Fig. 2 is an enlarged front view, broken out between its ends, of that part of the warp stop-motion illustrated in Fig. 1; Fig. 3 is a top plan view of the left hand end of the mechanism shown 55 in Fig. 2; Fig. 4 is a transverse sectional detail on the line 4-4, Fig. 2, looking toward the right; Fig. 5 is a detached view of one of the end supports, to be referred to; Fig. 6 is a view of the two-part pivot on which 60 the lease-rod guide is fulcrumed; Fig. 7 is a sectional detail similar to Fig. 4, but showing a released detector in the rear bank of detectors, to illustrate the visibility of such detector when the loom has been stopped 65 thereby.

Stands A^x opposite each other on the loom side support the novel position of the warp stop-motion between the whip-roll and the harnesses II, Fig. 1, at a convenient distance 70 back of the latter. The head a of a bracket having a depending and frontwardly curved foot a' is mounted on each stand A^x, each foot having a bearing a² for a transverse feeler rock-shaft f having attached upturned 75 arms f' near its ends, Fig. 2. A bifurcated ear a³ on each bracket head has upright parallel slots a⁴, and the upper end of each foot a' has two parallel and vertical saw-cuts a⁵ made in its inner face, Fig. 2, a 80 horizontal pin a⁶ being driven into each cut, to support and position in parallelism the detector guides or bars a⁷, the ends of the latter being dropped into opposite saw-cuts and resting on the pins. Each bar a⁷ serves 85 as a guide for a series or bank of vertically movable drop-detectors d, longitudinally slotted at d' for the reception of the bar, and also to serve as a warp-eye, as shown in Fig. 4. The two banks of detectors are 90 suspended from and hang below the warp-threads w, w'; between the lease-rods L, L', and it will be apparent that a very small portion of a detector is visible above the warp at any time, so that the locating of a 95 released detector must be undertaken below

the warp. Herein the ends of the lease-rods are extended through elongated eyes 1 of guide members 2, which permit vertical movement of the rods with the warp while limiting fore and aft movement of said rods. Endwise movement of the lease-rods is limited by end plates 3, each plate having holes 4, Fig. 5, for the reception of bolts 5 passed through the slots of the ears a^2 , said bolts clamping the plates 3 in vertically adjusted position on the inner faces of the ears, the enlarged ends 6 of a plate 3 crossing the eyes 1 opposite the ends of the lease-rods. Each plate 3 has a central hole 7 and an intersecting upright groove 8 on its inner face, the groove receiving lugs 9, Fig. 6, on the outer end of a cylindrical member 10 of a pivot device, internally threaded at 11 for the reception of the attaching screw 12 when passed through the hole 7, the screw thus locking the member 10 on the end plate while the lugs 9 prevent rotation of such member. The member 10 forms a fulcrum for the lease-rod guide 2, the latter having a hole 13, see dotted lines Fig. 3, for the reception of said member 10, the rectangular head 14 of the latter being provided with a vertical slot 15 crossed near its lower end by a transverse pin 16. A rod 17 constituting a warp-rest is dropped into the opposite slotted heads 14 and is supported in the slots 15 thereof by the pins 16, so that said warp-rest can be readily inserted or removed, and in a similar manner the detector guides a^7 can be easily inserted in or removed from their supports, previously described, in the upper ends of the bracket feet a' . The seats thus made for the warp-rest and for the detector guides are easily constructed and reduce the cost of manufacture materially.

Transverse back-stop bars b , b' are bolted to the front and rear edges of the feet a' to serve as stops or supports for released detectors in the front and rear banks, respectively, when co-operating with the feeler, and it will be seen by inspection of Figs. 2, 4 and 7 that the front bar b for the greater part of its length is quite shallow, its upper edge being so low down that the lower ends of the detectors in the rear bank are clearly visible from the loom side. That is, beneath the lower ends of the front bank of detectors and the top of the back-stop b there is a clear space through which the weaver can see not only the lower ends of the detectors of the rear bank, but he can also see plainly a released detector, as d^{20} , (see dotted lines Fig. 2) in such rear bank, and can thus as readily locate it as if it were in the front bank.

We have shown L-shaped brackets c bolted to the back-stop b' and extended frontward horizontally beneath the two backstops, Fig. 4, bosses c' on the front ends of the said

brackets loosely embracing the shaft f adjacent the bearings a^2 , as in Fig. 2. Horizontal ribs c^2 on the lower portions of the brackets c support slides f^3 pivotally connected by short links f^2 with the rocker arms f' , the slides having upright ears f^4 which carry transversely extended flat plates f^5 which serve as feelers. Lugs c^6 overhang the slides f^3 to serve as guides or stops for preventing any tipping movement of the said slides on the ribs c^2 . The feelers f^5 are reciprocated back and forth beneath the detectors by the normal rocking motion of the shaft f , see Fig. 4, the warp-threads while intact maintaining the lower ends of the detectors above the substantially horizontal path of movement of the feelers. When a warp-thread fails its detector will drop into abnormal position, as at d^{20} , Fig. 7, and will engage the feeler f^5 corresponding with the rear bank of detectors, to thereby arrest the feeler device as a whole on its rearward or feeling stroke, the back-stop b' serving to hold the released detector against backward pressure. In a similar manner the back-stop b will act when a released detector in the front bank engages its corresponding feeler f^5 .

The means for effecting the normal rocking of the rock-shaft f and for bringing about the stoppage of the loom when arrest of the feeler device is caused by a released detector may be of any suitable or well known character, of which there are numerous examples in the art. One of these devices is shown and described in United States Patent No. 797,671 granted to Draper, August 22, 1905. The link 27 in that patent corresponds to the link 23 partly shown herein, said link 23 being connected with a rocker-arm 22 loose on the shaft f , which latter has fast upon it an adjacent collar 20. A spring 21 connected with said collar and rocker-arm provides a connection between said arm and shaft which will yield when a released detector engages and arrests the normal vibrational movement of the feeler. As shown in Fig. 2 a lateral lug 24 on the hub of arm 22 is adapted to engage a similar lug 25 on a collar 26 fast on the shaft, (said lugs being shown by dotted lines in Fig. 2) so that the retracting stroke of the feeler members f^5 is effected positively when the link 23 is drawn downward.

While the lower ends of both banks of detectors are easily seen at all times by the weaver, whether or not the feeler device is in motion, yet the location of the latter well below the detectors, and the movement of the feeler members f^5 in a substantially horizontal path, tend to still further open up to view this part of the warp stop-motion, as will be apparent.

When the loom stops it is convenient for

the weaver to ascertain instantly if such stoppage is due to a warp fault. To this end an arm 27 fast on one end of the feeler rock-shaft *f* is connected by a link 5 28, Figs. 1 and 2, with a bell-crank 29, 30 conveniently fulcrumed on one of the bolts 5 hereinbefore referred to, the arm 30 being shaped as a handle, and by swinging said handle to the left, Fig. 1, the feelers *f* will 10 be moved in the direction of the feeling stroke if the warp-threads are intact, showing that loom stoppage was not due to a warp fault. If a released detector has brought about loom stoppage then the 15 handle 30 cannot be swung to the left and the weaver knows that a warp-fault has brought about the stoppage of the loom.

Having fully described our invention, what we claim as new and desire to secure 20 by Letters Patent is:

1. In a warp stop-motion for looms, vertically movable detectors arranged in two parallel banks and suspended from and maintained elevated by intact warp-threads, 25 said detectors being almost wholly below and concealed by the warp-threads, fixed guides for said detectors, located below the warp, the lower ends of the detectors extending below said guides, a stationary back-stop for each bank, to support the rear edge 30 of a released detector, the front stop having its upper edge at a distance below the lower ends of the detectors of the front bank, to leave an unobstructed sight opening through 35 which the lower ends of the detectors of the rear bank, and a released detector in such bank, can be clearly seen by the weaver, connected feeler members, one for each bank of detectors, and means normally acting to 40 vibrate said members in a horizontal path below the back-stops, a released detector engaging one of the feeler members and arresting movement thereof, such arrangement of the front stop and relative location of the 45 feeler members permitting a released detector in either bank to be readily located.

2. In a warp stop-motion for looms, opposite, fixedly supported brackets each having a depending, frontwardly curved foot, a 50 feeler rock-shaft supported by the lower ends of said feet, open seats in the upper portions of said feet, located opposite each other, transverse and parallel detector-guides removably mounted in the seats, a 55 bank of longitudinally slotted detectors loosely strung upon each guide, and suspended from the warp-threads between the lease- rods, said lease- rods, positioning means for the same, mounted on the brackets, a plurality of fixedly connected feeler members, one for each bank of detectors, supporting means on the inner faces of the bracket feet, on which the feeler members are slidably sustained, and operating con-

nnections between the rock-shaft and said 65 members to effect normal vibration thereof in a substantially horizontal path.

3. In a warp stop-motion for looms, opposite, fixedly supported brackets each having an upturned ear, an end-plate bolted 70 to each ear on its inner face, a pivot member carried by and extended inwardly from each end-plate, a fore and aft guide member fulcrumed on the inner end of each of the pivot members and having eyes at its 75 ends opposite the extremities of the adjacent end-plate, lease-rods loosely extended through the eyes and vertically supported by the warp threads, the end-plates limiting endwise movement of the lease-rods, a 80 head on the inner end of each pivot member, having an upright slot and a pin crossing the lower end of such slot, and a warp-rest detachably held in the slotted heads and 85 vertically supported by the transverse pins, combined with two banks of detectors suspended from and hanging below the warp-threads between the lease-rods, the warp rest being located between the two banks of detectors.

4. In a warp stop-motion for looms, vertically movable controlling-detectors arranged in two transverse, parallel banks, suspended from and maintained elevated by intact warp-threads, a pair of feeler 95 members normally vibrating back and forth in a substantially horizontal path below the banks of detectors and adapted to be engaged and arrested by a released detector, and a fixed, transverse bar for each bank, 100 to support the rear edge of a released detector when in engagement with its feeler member, the upper edge of the front bar being below the lower ends of the front bank of detectors and exposing to view the 105 lower ends of the detectors in the rear bank, whether the latter detectors be in normal or abnormal position.

5. In a warp stop-motion for looms, opposite, fixedly supported brackets each having 110 a depending, frontwardly extended foot, a feeler rock-shaft supported by the lower ends of said feet, transverse and parallel detector-guides sustained by the upper portions of the feet, a bank of longitudinally 115 slotted detectors loosely strung upon each guide and suspended from and almost wholly below the warp-threads, fixedly connected feeler members, one for each bank, supports on the inner faces of the bracket feet, on 120 which the feeler members are slidably sustained, operating connections between said feeler members and the rock-shaft, to effect normal vibration of the former in a substantially horizontal path, and a back-stop 125 for each bank of detectors, said stops being fixedly mounted on the front and rear edges of the bracket feet above the feeler path,

each stop serving to support the rear edge of a released detector in the corresponding bank, the upper edge of the front stop being below the lower ends of the detectors of 5 the front bank, to permit an unobstructed view of the lower end of a released detector in the rear bank.

In testimony whereof, we have signed our

names to this specification, in the presence of two subscribing witnesses.

WALLACE I. STIMPSON.
ALONZO E. RHOADES.
